UNITED STATES PATENT OFFICE.

CHARLES W. MURDOCK, OF OMAHA, NEBRASKA.

MAIL-BAG CATCHING AND DELIVERING APPARATUS.

SPECIFICATION forming part of Letters Patent No. 760,470, dated May 24, 1904.

Application filed September 16, 1903. Serial No. 173,471. (No model.)

To all whom it may concern:

Be it known that I, CHARLES W. MURDOCK, of Omaha, in the county of Douglas, State of Nebraska, have invented certain new and useful Improvements in Mail-Bag Catching and Delivering Apparatus; and I do hereby declare the following to be a full, clear, and exact description of the same, reference being had to the accompanying drawings, forming a part 10 of this specification, and to the letters of reference marked thereon.

This invention relates to improvements in apparatus designed to facilitate the catching and delivery of mail-bags from rapidly-moving trains, the objects of the invention being to provide a simple and effective apparatus which will catch the incoming pouch and automatically eject the outgoing pouch in proper direction to be caught by a receiver located 15 beside the track, the ejection of the outgoing pouch being controlled by the incoming pouch or a relatively fixed part associated with the support for the incoming pouch before it is taken by the catcher, whereby the outgoing 20 pouch is always ejected at the proper instant to enter the fixed receiver and may as a consequence be ejected transversely of the line of movement of the car and into a receiver having its entrance arranged opposite or substantially 25 opposite thereto.

Broadly, the invention consists in an ejecting mechanism with suitable power connections for operating the same controlled by or set in action by the catching mechanism when moved 35 by the impact of the incoming pouch or by contact with a relatively stationary part located alongside the track.

Further, the invention consists in certain novel details of construction and combinations 40 and arrangements of parts, all as will be now described, and pointed out particularly in the appended claims.

Referring to the accompanying drawings, Figure 1 is an elevation of a portion of the side 45 of a car equipped with an apparatus embodying the present improvements. Fig. 2 is a vertical section taken transversely of Fig. 1. Fig. 3 is a detail sectional elevation, on an enlarged scale, of the catcher and controlling mechanism for the ejector. Fig. 4 is an enlarged sec-

tion showing one of the catcher-supporting brackets in elevation. Fig. 5 is a section vertically through one of the catcher-brackets, illustrating the air passages and ports therein. Fig. 6 is a detail perspective view of one of the 55 brackets with one end of the catcher in position ready for operation to release the ejector. Fig. 7 is a diagrammatic illustration of a modified arrangement of operating mechanism for the ejector. 60

Like letters of reference in the several figures indicate the same parts.

The letter A in the accompanying drawings indicates a portion of a car of any of the ordinary or preferred types now commonly employed in the railway mail-service. 65 This car, as usual, has a side door-opening, and the catching and delivering apparatus is located in proximity thereto.

In the present apparatus the two mechanisms are associated for co-operation—that is to say, the ejecting or delivering mechanism is dependent for its operation upon the positioning of the catching mechanism to take an incoming pouch and the subsequent movement 70 of the same due to the impact of an incoming pouch or to the catcher striking some previously-set part which will give it the requisite movement at the proper instant. 75

The catching mechanism illustrated embodies a catcher-arm B, journaled in a V-shaped base B², but held against longitudinal movement by suitable collars or shoulders b. The V-shaped base B² is in turn mounted on or formed integral with a rod or extension-bars B³, adapted to slide longitudinally in brackets C, located at each side of the door-opening, the said catcher being reversible in the usual manner by turning it end for end in the supporting-brackets. Springs D are provided for taking up shock due to the impact of the incoming pouch, and in the preferred arrangement these springs are interposed between sleeves E and the brackets C, the catcher being directly supported in the sleeves and in 95 position to rest against one or the other of the same when in catching position.

The movement of the catcher due to impact of the pouch or to contact with some body serving the same purpose and operating to 100

compress the spring is utilized to release the 5
ejecting mechanism for the outgoing pouch,
and as a most convenient and efficient arrangement
the said ejecting mechanism is located
below the floor-level of the car. This arrangement
permits the pouch to be placed in position
with facility and delivers it below the
platform-level out of the way of injury to itself
or to bystanders. A suitable receptacle
10 formed by side walls E and slotted inclined
bottom E² is formed below the floor of the car
and access thereto is had through a trap-door
E', which may be lifted by the clerk, the pouch
or pouches put in position, and the door again
15 closed. The exit of the receptacle is closed
by a door F, mounted on a horizontal axis
above the level of the opening and preferably
having an upwardly-extending portion F',
which swings inwardly and downwardly as the
20 door swings upwardly and outwardly to aid in
forcing the pouch downwardly and out. To
further aid in the ejection of the pouch or
pouches and to give them a positive movement
transversely of the line of car movement, eject-
25 tor-bars G are hung on a horizontal axis in
position to swing across the receptacle, as in-
dicated in dotted lines, Fig. 2, and, if desired,
the ends of said bars may work through slots
in the inclined bottom E² of the receptacle, as
30 shown.

The door F and the ejector-bars are both
adapted to be operated simultaneously by
power, which, with the apparatus shown in the
drawings with the exception of Fig. 7, is com-
35 pressed air operating through a piston in a
cylinder H, the piston being connected with
the door through an operating-rod H' and arm
h. The piston is also connected with the ejector-bars
40 through a link H², jointed to the rod
H' and to an arm G' on the said bars or on the
shaft carrying said bars.

Compressed air for the cylinder may be
taken from the train-pipe system, and the
movement of the piston is controlled by a
45 valve mechanism in a pipe I, leading from the
cylinder up to the brackets C. As shown,
the pipe I is branched and is an exhaust-pipe,
the ends of the branches being in or in proxim-
50 ity to the brackets C in position to be closed by
suitable valves, and, as shown, the sleeve E may
constitute such a valve, being provided with
ports e', adapted to register with the ports of
the pipes when the sleeves are moved in a di-
55 rection to compress the springs. Each branch
is provided with a stop-cock K, whereby the
forward branch may be closed when the car
is running in either direction, or both may
be closed when no delivery is to take place.

The stop-cocks K are provided with han-
60 dles k, preferably on the outside of the car,
and slotted for the reception of a pin or pro-
jection k' on the base of the catcher, whereby
the valve will be opened or closed by swing-
ing the catcher into or out of catching posi-

tion, and thus the air is effectually cut off at 65
all times save at the moment when delivery
is to be made, and then only the proper pipe
is opened.

While, as has been before pointed out, the
sleeves themselves may be formed with ports 70
and serve as the controlling-valves, a suit-
able valve structure, such as shown, with its
valve-stem E⁴ in position to be struck by the
sleeve or a part moving therewith, is prefer-
ably employed, as it may be more readily re- 75
newed or repaired in case of injury or wear.

Each sleeve is preferably provided with
wings L, working in grooves in the brackets
to prevent turning, and if a port be formed
in the sleeve it usually extends through one 80
of the wings or projections, as shown in Fig.
5, thereby facilitating the accurate fitting of
the sleeve as a valve.

To guard against the possible operation of
the ejecting mechanism by a push on the 85
catcher before it is swung up into proper po-
sition to catch a pouch, the said catcher is
provided with a projection M, extending rear-
wardly past the front end of the sleeve and
adapted to contact with the end of the bracket 90
or a projection M' thereon and prevent lon-
gitudinal movement at all times save when
the catcher is swung out. In the latter posi-
tion the projection on the catcher rises above
the projection on the bracket and the catcher 95
is free to move rearwardly when sufficient
pressure is applied to overcome the spring.

The end of the catcher-arm B is made in
spatula shape, but with a straight forward
edge N to insure its contact with an arm or
other yielding body placed alongside the 100
track to operate the ejecting mechanism if no
pouch is to be caught or as an additional
means for effecting the operation in conjunc-
tion with the incoming pouch, although this
shaped catcher-arm is useful in effecting the 105
disengagement of the incoming pouch from
its supports in some forms of catching mech-
anism.

The straight edge of the arm should occupy 110
a vertical position both when at rest down
beside the car and when swung out into op-
erative position, and in order to control its
movements its inner end is provided with a
head O, adapted to bear against the side of 115
the forward end of the bracket or against the
under side of the projection M' when the
catcher is swung out and against the outer
side of a projection O' when the catcher is
swung down, whereby the catcher-arm will be 120
turned into proper position, as aforesaid.
When the catcher is turned down, the head O
may lie in front of a projection P, which will
serve as an additional means to prevent the
rearward movement of the catcher except 125
when it is turned up into catching position.
Obviously either or both means for prevent-
ing the longitudinal movement of the catcher

may be employed, and hence I do not wish to be limited to any particular means save as specified in the claims.

Obviously power other than compressed air may be employed to operate the ejecting mechanism. Thus it is practicable to employ a spring or springs, which may be put under tension by the clerk or otherwise and held by a suitable catch mechanism until released by the operation of the catcher. In Fig. 7 one such arrangement is shown, a spring Q, working in a suitable barrel or support, taking the place of the power-cylinder. The operating-rod in this instance is connected through a lever Q' with a vertically-extending rod Q², having a hook q at the upper end adapted to hook over a lever or catch R, journaled in the side of the car and having a part projecting into position to be struck by the end of the catcher-rod when the latter is moved rearwardly, as before explained. The movement of the catch by the catcher releases the hook, permitting the spring to expand and operate the ejecting mechanism. With this form of device the apparatus is set by the clerk, who draws the rod Q² up and throws the catch into engagement therewith to hold the spring under tension.

In operation the clerk places the filled pouch or pouches in the receptacle beneath the floor and at the proper moment grasps the handle of the catcher and swings the same out into catching position. If compressed air is the motive power for the ejecting mechanism, this movement will open the proper cock, leaving the other closed. The incoming pouch will cause the catcher to move toward the rear and release the ejecting mechanism, the movement necessary to effect this being about the same as the movement ordinarily made by the catchers now in use, and hence the clerk is not subjected to any additional jar, nor is he in any danger of being struck by any of the moving parts of the ejecting mechanism, as all such mechanism is located below the car and out of the way. No additional effort is required on his part, although in case no pouch is caught he may by pressing the catcher toward the rear compress the spring and release the ejecting mechanism to discharge the outgoing pouch.

What I claim as my invention, and desire to secure by Letters Patent, is—

1. In a mail-pouch catching and delivering apparatus, the combination with a power-operated ejecting mechanism for the outgoing pouch, of a releasing mechanism therefor and a catcher controlling said releasing mechanism; substantially as described.
2. In a mail-pouch catching and delivering apparatus, the combination with a power-operated ejecting mechanism for the outgoing pouch, of a rearwardly-movable catcher and a controlling mechanism for the ejecting mech-

anism operated by the catcher when moved rearwardly; substantially as described.

3. In a mail-pouch catching and delivering apparatus, the combination with a power-operated ejecting mechanism for the outgoing pouch, of a rearwardly-movable catcher, a spring for normally holding said catcher against rearward movement and a controlling mechanism for the ejector mechanism operated by the catcher when moved rearwardly; substantially as described.

4. In a mail-pouch catching and delivering apparatus the combination with the ejecting mechanism, and catcher, of a power mechanism for operating the ejecting mechanism and connections operated by the catcher for controlling the power mechanism; substantially as described.

5. In a mail-pouch catching and delivering apparatus the combination with the ejecting mechanism and rearwardly-movable catcher adapted to be swung out into catching position, of a power mechanism for operating the ejecting mechanism, with controlling connections therefor operated by the rearward movement of the catcher and stops for holding the catcher against rearward movement save when swung out into catching position; substantially as described.

6. In a mail-pouch-delivering apparatus, the combination of an ejecting mechanism for the outgoing pouch, a power mechanism for operating the same and a controlling mechanism for said power mechanism embodying a rearwardly-movable arm on the side of the car, journaled to swing out into position to contact with an object located alongside the track; substantially as described.

7. In a mail-pouch catching and delivering apparatus, the combination with the receptacle for the outgoing pouch located beneath the floor of the car, a door for closing the exit-opening of the receptacle, an ejector for ejecting the pouch when the door is opened and a power mechanism for opening the door and operating the ejector, of a catcher for the incoming pouch and controlling connections between the catcher and power mechanism; substantially as described.

8. In a mail-pouch catching and delivering apparatus, the combination with the receptacle for the outgoing pouch embodying an entrance-opening in the car and an exit-opening outside of the car, of a door for closing the exit-opening to prevent the escape of the pouch, an ejector and mechanism for simultaneously operating the door and ejector; substantially as described.

9. In a mail-pouch catching and delivering apparatus, the combination with a receptacle for the outgoing pouch formed with a bottom inclined toward the exit-opening and a door for closing said opening to prevent the escape of the pouch, of an ejector for the pouch and a

power mechanism for simultaneously opening the door and operating the ejector; substantially as described.

10. In a mail-pouch catching and delivering apparatus, the combination with the receptacle for the outgoing pouch located beneath the floor of the car and having a bottom inclined toward the exit-opening, and a door for closing said opening to prevent the escape of the pouch, of an ejector for the pouch and a power mechanism for simultaneously opening the door and operating the ejector; substantially as described.

11. In a mail-pouch catching and delivering apparatus, the combination with the catcher adapted to swing on a horizontal axis and move rearwardly and a spring for resisting such rearward movement, of a fixed projection and a projection on the catcher coöperating therewith to prevent rearward movement of the catcher when swung down out of operative position, and ejecting mechanism adapted to be released by the rearward movement of the catcher-arm; substantially as described.

25 12. In a mail-bag catching and delivering apparatus, the combination with the brackets in which the catcher is hung of the catcher journaled in said brackets and having a catcher-arm made in spatula shape at the end and capable of a limited rotary movement and adapted to move rearwardly and projections on one of the brackets and catcher-arm, respectively for maintaining the end of the arm in vertical position both when the arm is in catching 35 position and when swung down against the side of the car, and ejecting mechanism adapted to be released by the rearward movement of the catcher-arm; substantially as described.

13. In a catching and delivering apparatus 40 for mail-pouches, the combination with the ejecting mechanism, and a piston and compressed-air cylinder for operating the same, of a catcher for the incoming pouch and a

valve operated by said catcher and controlling the air for operating the piston; substantially as described.

14. In a catching and delivering apparatus for mail-pouches, the combination with the ejecting mechanism and a piston and compressed-air cylinder for operating the same, 50 of a catcher for the incoming pouch, a bracket in which said catcher is supported, a valve for an air-pipe leading to the cylinder mounted in proximity to the bracket in position to be operated by the catcher when moved by the impact of the incoming pouch; substantially as described.

15. In a catching and delivering apparatus, for mail-pouches, the combination with the ejecting mechanism, compressed-air motor for 60 operating the same and a controlling-pipe for said motor, of a reversible catcher and oppositely-arranged valves in said pipe with which the catcher coöperates, whereby the motor may be operated by the catcher when set in 65 either direction; substantially as described.

16. In a catching and delivering apparatus for mail-pouches, the combination with the ejecting mechanism, compressed-air motor for 70 operating the same and a controlling-pipe for said motor, of a reversible catcher, oppositely-arranged valves in said pipe with which the catcher coöperates and cocks for cutting out one or both of said valves; substantially as described.

75 17. In a catcher for mail-pouches, the combination with the brackets, of the catcher-base journaled in said brackets and the catcher-arm formed spatula at the end and journaled in the base whereby its end may be turned into vertical position when in operative or in inoperative position; substantially as described.
